United States Patent Office

Des. 188,651
Patented Aug. 23, 1960

188,651

PLAYSUIT

Lester M. Cutler, Bronx, N.Y. (261 Parkside Drive, Roslyn Heights, New York, N.Y.), and Josephine A. Sabatini, Roslyn Heights, N.Y. (1086 E. 180th St., New York, N.Y.)

Filed Dec. 22, 1959, Ser. No. 58,764

Term of patent 14 years

(Cl. D3—17)

Fig. 1 is a front elevational view of a playsuit showing our new design;

Fig. 2 is an exploded view thereof showing the blouse and pants, the back of the pants being similar in appearance to the front;

Fig. 3 is a front elevational view, of the blouse, the skirt portion thereof being shown in open position; and

Fig. 4 is a rear view thereof.

We claim:

The ornamental design for a playsuit, substantially as shown and described.
